BY

J. E. Bookstaver ATTORNEY.

UNITED STATES PATENT OFFICE.

SEWARD D. SCHENCK, OF BINGHAMTON, NEW YORK.

DESIGN FOR A SPOON.

SPECIFICATION forming part of Design No. 23,690, dated October 16, 1894.

Application filed July 27, 1894. Serial No. 518,777. Term of patent 3½ years.

To all whom it may concern:

Be it known that I, SEWARD D. SCHENCK, a citizen of the United States, residing at Binghamton, in the county of Broome and 5 State of New York, have invented and produced a new and original Design for Spoons, of which the following is a specification, reference being had to the accompanying drawing, showing a part thereof.

10 The figure is a perspective view of my design the leading features of which consist in the representation in the bowl of a public

building, and the handle consisting of the representation of the standing figure of a man having in his hands a satchel and overcoat 15 and standing upon a vertical scroll work reaching to the bowl of the spoon.

What I claim as my invention is—

A design for a spoon substantially as herein described and shown.

SEWARD D. SCHENCK.
